ARCHITECTURAL SCREEN OR SIMILAR ARTICLE

Erwin Franz Hauer, New Haven, Conn.

Application April 26, 1957, Serial No. 45,909

Term of patent 14 years

(Cl. D18—2)

Fig. 1

Figure 1 is a front elevation of an architectural screen or similar article showing my new design;

I claim:

The ornamental design for an architectural screen or similar article, as shown.
